SUCTION CLEANER

Vernon E. Carlson, Canton, Ohio, assignor to The Hoover Company, North Canton, Ohio, a corporation of Ohio

Application December 31, 1938, Serial No. 248,755

2 Claims. (Cl. 306—13)

The present invention relates to suction cleaners and particularly to new and improved handle control mechanism in a suction cleaner.

It is an object of the invention to provide a new and improved suction cleaner. It is another object to provide new and improved handle controlling means in a suction cleaner. A further object is to provide a handle controlling mechanism composed of few parts, which are inexpensive to manufacture and easily assembled. Another object is to provide a handle supporting member which also supports a foot operated handle control lever. Further objects and advantages of the invention will be apparent upon referring to the following specification and claims and the attached drawing, wherein:

Figure 1 is a side elevational view of a suction cleaner with parts broken away illustrating one embodiment of the invention;

Figure 2 is an enlarged perspective view of the embodiment shown in Figure 1, and

Figure 3 is a section along the line 3—3 of Figure 1.

An embodiment of the invention is disclosed in a suction cleaner comprising a main casing 5 having a nozzle 6 communicating with a passageway 7 extending to a fan chamber 8 communicating with an exhaust passageway 13 provided with a vertical flange 14 to which a dust bag 15 is removably secured. The casing 5 supports a motor housing 16 enclosing an unshown motor which drives the fan 17 to create suction and draw dirt-laden air from the surface being cleaned, through the nozzle 6, suction passageway 7, fan chamber 8 and discharges the dirt-laden air through the exhaust passageway 13 into the dust bag 15. The cleaner is supported on front and rear wheels 18 and 19 respectively.

The cleaner is propelled over the surface covering by means of a handle 20 removably disposed in a split socket 21 having a front wall 22, a split rear wall 23 and side walls 24 and 25. The handle socket 21 is pivotally mounted on the casing 5 by being journaled on a pivot pin 26 extending through the socket side walls and the spaced side walls 21, 27 of a handle bracket 28, the socket 21 being arranged exteriorly of the bracket 28. The bracket 28 has a back wall 29 secured to the exhaust flange 14 and a pair of lateral offsets 30 and 31 which are mounted on the casing 5 above the exhaust passageway 13.

Segment means 35 are formed on the lower defining edge of the socket side wall 25 and includes stops 36, 37 and 38 and segmental recesses

40, 41 and 42 to provide different operating ranges for the handle 20.

A handle control lever 46 is provided at its rear end with a pair of spaced bearings 47 mounted on a pivot pin 48 which has one end journaled in an upstanding lug 50 formed integrally with the bottom flange 31 of the handle bracket 28 and the other end is supported in a side wall 27 of the handle bracket 28. In order to properly position the control lever 46 on the pivot pin 48 a flat spring 52 has one end secured on the control lever 46 and its opposite end is disposed in an annular recess 53 in the pivot pin 48.

Formed integrally with the control lever 46 is a detent means which comprises a pawl 54 projecting from the body 55 of the control lever 46. The pawl 54 engages the segment surfaces to hold the handle in the selected operating range.

Also formed integrally with the control lever 46 is a laterally extending arm 57 provided at its outer end with a foot operated button 58 to actuate the handle control means. The lever arm 57 is offset with respect to its pivotal axis 48 and extends through a marginal slot 59 in the motor housing 16.

The bottom wall 31 of the handle bracket 28 is provided with an opening 60 in which one end of a spring 61 is anchored and rests upon the casing 5, and the opposite end of the spring is anchored about an annular bead 63 formed in the body portion 55 of the handle control lever 46. The spring 61 operates to at all times urge the lever 46 upwardly to cause the pawl 54 to engage the segment surfaces to lock the handle in the selected position. A tab 65 is formed on the lever arm 57 to limit forward and downward movement of the control lever 46 by engagement with the cleaner casing 5.

The weight of the handle is counterbalanced by a torsion spring 66 arranged within the handle socket 21 and about the handle pivot 26. One end 67 of the spring rests on a lug 68 mounted on a side wall 27 of the handle bracket, and the opposite end 69 is anchored against a lug 70 formed on a member 71 rigidly secured in the handle socket 21. The member 71 is provided with laterally offset stops 72 which engage the inclined surfaces 73 on the side walls 27 of the handle bracket to limit movement of the handle in its lowest position, the inclined surfaces 73 cooperating with the segment stop 38 to define the low operating range of handle movement. Upward movement of the handle is limited by engagement of the lower end 74 of the handle socket front wall 22 with the inclined edges 75 of the handle 55

bracket side walls 27. The member 11 is provided with an upstanding tongue 33 for reception of the screw 84 to anchor an electrical plug 85 in the handle socket 21.

5 In operation assume that the handle is in its intermediate operating position as shown in Figures 1 and 2, the pawl 54 being disposed in the recess 41 to hold the handle in this position. In order to lower the handle to the low operating 10 range, the operator places his foot on the button 58 and depresses the latter causing the control lever 46 to pivot counter clockwise, as viewed in Figure 2, and the pawl 54 to move out of the recess 41. The handle may now be lowered and 15 thereafter the operator removes his foot from the button 58, the spring 61 pivoting the control lever 46 upwardly to move the pawl 54 into the recess 42 and permit free movement of the handle in the operating range defined by stops 38 20 and 73. Downward movement of the handle is limited by the stops 72 engaging the inclined surfaces 73 on the handle bracket 28. The handle may be moved upwardly without manipulating the control lever 46 since the pawl 54 rides 25 along the cammed surfaces 80 and 81 on the segment 35 against the force exerted by the spring 61.

From the foregoing it will be perceived that I have provided a handle control that is inexpensive to manufacture and includes very few 30 parts. The handle bracket is formed of one stamping which not only supports the handle but is provided with means to pivotally support the handle control lever 46. The control lever, 35 detent and foot operating portions are formed in one stamping and are entirely supported on the handle bracket.

It is to be understood that the protection herein applied for is not confined to the particular 40 combinations of features or elements set out in

the following claims. Protection is herein applied for, for any one or more of the features or elements referred to in the following claims or described in the foregoing specification or shown in the accompanying drawing, either independently or in combination. 5

I claim:

1. In a suction cleaner, a casing, a stamping removably mounted on said casing and having a pair of spaced upstanding arms and a lug spaced 10 from one of said arms, a handle pivotally supported on said spaced arms, segment means mounted on said stamping and connected to said handle, a manually operable handle control lever pivotally mounted on said lug and said one arm, 15 and detent means operated by said lever for removable engagement with said segment means to releasably hold said handle in restricted and adjusted positions, said stamping supporting said handle, segment means, detent means and handle control lever for removably mounting the same on said casing as a unit. 20

2. In a suction cleaner, a casing, bracket means mounted on said casing, said bracket means having integrally formed spaced upstanding arms and a bearing support spaced from one of said bracket arms, a handle pivotally mounted on said spaced bracket arms, segment means formed in a wall of said handle, a bearing support formed in said one bracket arm, a manually 30 actuated handle control lever pivotally mounted in said bearing supports, and detent means integral with said control lever and normally engaging said segment means to hold said handle in restricted adjusted positions, manipulation of 35 said control lever disengaging said detent means from said segment means to permit movement of said handle with respect to said casing.

VERNON E. CARLSON. 40
